UNITED STATES PATENT OFFICE.

PETER PELLETIER, OF LAWRENCE, MASSACHUSETTS.

FILLING-TENSION DEVICE.

Application filed April 17, 1925. Serial No. 23,942.

To all whom it may concern:

Be it known that I, PETER PELLETIER, of Lawrence, in the county of Essex and State of Massachusetts, a citizen of the United States, have invented a new and useful Improvement in Filling-Tension Devices, of which the following is a specification.

My invention is adapted particularly for use on dobby looms and is especially useful with looms for weaving silk, artificial silk and other materials of similar character. It is well known that in weaving these materials there are often shiny picks and kinky filling due to the fact that all the filling is not drawn from the bobbin under equal tension and any change in the tension, however slight, in laying the filling between the warp threads mars more or less the sheen of the cloth so that it will look more or less spotted.

My invention is intended to overcome this fault by putting the filling under tension after it has been laid in the warp and before it has left on its return pick.

My invention consists in connecting to each side of two harnesses, which may be supplied for the purpose, a pair of tension rods so that as the harnesses are reciprocated in opposite directions by the usual mechanism these rods will also be reciprocated vertically.

My invention will be understood by reference to the drawings in which it is shown in its preferred form, only so much of the loom being shown as is necessary to point out my invention.

Figure 1 is a cross section of a loom embodying my invention, looking from the breast beam toward the harness.

Fig. 2 is a vertical section on line 2—2 of Fig. 1.

Fig. 3 is an enlarged sectional detail of parts shown in Fig. 2.

Fig. 4 is an enlarged elevation of one of the harnesses.

Fig. 5 is a section on line 5—5 of Fig. 4.

Fig. 6 is a plan view showing the relation of the breast beam to the harnesses to which my tension rods are attached.

Fig. 7 is a section on line 7—7 of Fig. 6.

Fig. 8 shows in perspective a portion of the breast beam with one of the rod guides attached thereto.

Fig. 9 shows one of the rod guides attached to the frame in front of the harnesses.

Figs. 10 and 11 show details of the yoke, and

Figs. 12 and 13 show diagrammatically the operation of my improvement. 60

I have shown in the drawings only the two harnesses to which my improvement is attached. In practice there will be in addition the usual warp-carrying harnesses which may be located with their operating mechanism between the harnesses shown. 65

1 is the frame which is of the usual construction in dobby looms, showing at its upper left hand corner at 2 a portion of the dobby mechanism, which being well known 70 is not herein described. This mechanism comprises among other parts the usual harness levers 3 and as shown a yoke 4 of new construction to which are attached the usual cords 5 running on pulleys 6 and carrying 75 at their lower ends the front harnesses 7. The rear harness is hung from cords 51 and is operated in a usual manner. I prefer to use a yoke of the construction shown in Figs. 10 and 11 comprising two closed loops, 80 as being more positive in character. While there may be any convenient number of harnesses, I have shown only the two necessary to illustrate my invention, the other harness being hung between the harnesses 7 85 and 8, the frame being wide enough to support the necessary number of harness levers, etc. The front harness carrying my tension rods is marked 7 and the rear harness is marked 8. 90

As it is very desirable that there should be as little vibration to my tension rods as possible, I have provided guides 9 for the back harness and other guides 10 for the front harness, these guides being metal strips 95 against which these harnesses slide, the guide 9 extending downward from the arch of the frame 1 towards the floor and being attached thereto by springs 11, while the guides 10 in like manner extend down in front of and 100 below the lowest position of my tension rods. The guides 10 are slotted as at 12 and 13 to allow my tension rods to pass through them and to have a vertical movement therein corresponding with the vertical movement of 105 the harnesses (see Fig. 9). 14 is the breast beam which carries guide straps 15 mounted thereon, each guide strap having preferably a horizontal part by which it is attached to the breast beam and a vertical part having 110 slots 16 and 17 in which the ends of the tension rods may reciprocate, this vertical por-

tion of the guide strap being set out from the breast beam to allow the ends of the tension rods to be upset or otherwise prevented from being accidentally withdrawn therefrom (see Figs. 3 and 8).

The tension rods are marked 19, 20, 21 and 22. They are shown in section in Figs. 1 and 7, in side view in Figs. 2 and 3 and in plan in Fig. 6. It will be understood that two of these rods 20 and 21 are mounted in the rear harness and 19 and 22 in the front harness. 23 is the lay which is operated in the usual manner and its shuttle race is preferably slotted as indicated at 24 in Fig. 2, with narrow slots so as not to interfere with the movement of the tension rods when two of these rods are in their lowest position. The movement of the rods, that is of the harness containing them, being as usual is such that while the lay is moving and the race is swinging upward the rods will be up above the highest point of the arc of movement of the lay and hence will not interfere with the lay or shuttle when the parts are properly timed.

The utility and operation of my invention will be understood particularly from Figs. 12 and 13. In these figures the shuttle is indicated running to the shuttle box 25. In doing so it has laid the filling *a* in the warp from the further edge of the cloth, and the further end of the filling from the shuttle is indicated by the turn of the filling marked 26. It will be understood that the cloth is narrower than the distance between the rods 19 and 22. By the time the shuttle has reached the point indicated in Fig. 12 the harnesses change bringing the tension rods 19 and 20 into the positions shown in Fig. 13. The filling *a* which has just been laid in the warp extends from the point 26 to the shuttle, so it will be seen that the filling runs from this point to the shuttle between the rods 19 and 20. The harnesses then bring the rods into the position shown in Fig. 13 so that the rods 19 and 20 create a tension on the filling thread *a*, it being understood that the rods engage the filling at a point near their middle. While the rods 21 and 22 also have the same motion as the rods 19 and 20, bringing them into the positions shown in Fig. 13, as they lie outside the width of the cloth there is no filling thread for them to act upon at this time.

When the parts have come into the position shown in Fig. 13 the harnesses immediately move back into their original position separating the rod 20 from the rod 19 and the rod 21 from the rod 22, the other harnesses (not shown) being operated to open the shed as usual, and the shuttle is immediately returned through the shed as newly opened pulling the slack end of its thread at the salvage through the shed and going into the shuttle box at the opposite side of the

cloth. At this moment the harnesses move again so that the rods 21 and 22 engage the thread in the rear of the shuttle applying tension to it, thus drawing it up evenly into the wrap and then releasing it so that the shuttle may return in the same way back to the other side again. The rods 19 and 20 being outside of the width of the cloth are inactive at this moment although of course being moved by their harnesses.

It will of course be understood that the lay in its beating up co-operates in the usual way with the other parts.

So far as I know no means have ever been applied outside the shuttle to place the filling under tension, nor has any means been used to apply tension to the pick which has been laid in the filling to draw it smooth in the warp, it being the usual practice to rely upon the tension in the shuttle to do this. With delicate weaving, however, where exact evenness is required, such for example as in weaving silk, it is very essential that exactness in the laying of the filling shall be maintained in order that there may be no spots which will mar the sheen of the woven product, these spots occurring usually where there is unevenness of tension in the weaving. For these reasons therefore I do not limit myself to the precise form of the invention shown in the drawings, as I believe it may be otherwise embodied. It is not necessary in carrying out my invention that the harnesses shall be given a full movement. In fact, in operation I have found that the tension rod harnesses may be satisfactorily operated with but a half throw.

It will also be understood as stated above that my improvement may be used upon a loom having any desired number of harnesses properly mounted therein and operated thereby. For simplicity only two harnesses are shown.

What I claim as my invention is:

1. In a loom of the kind described having a shuttle and a breast beam, two harnesses and means for reciprocating them in opposite directions, each harness carrying a pair of rods extending horizontally therefrom across the path of the shuttle in the direction of the breast beam whereby when reciprocated vertically they will engage the shuttle thread and take up the slack therein.

2. In a machine of the kind described containing a breast beam, two harnesses, tension rods extending horizontally from said harnesses toward said breast beam, and guide plates located on said breast beam to receive and guide the ends of said rods as said rods are reciprocated by said harnesses.

3. In a machine of the kind described, a breast beam, two harnesses, means for reciprocating them vertically in opposite directions, vertical plates one pair located in front of said harnesses and the other in

the rear thereof to guide the harnesses in their vertical movement, said harnesses having tension rods extending from them toward the breast beam, and said front guide plates having slotted openings therein to assist in guiding said tension rods.

4. In a machine of the kind described,

tension rods mounted on each side of the warp, and means for operating them comprising harnesses whereby they will move ¹⁰ across the path of the shuttle thread and engage and take up slack therein.

PETER PELLETIER.
